US00D822229S

(12) **United States Design Patent** (10) **Patent No.:** **US D822,229 S**
(45) **Date of Patent:** **** Jul. 3, 2018**

(54) **CEILING TILE OR PANEL**

(71) Applicant: **durlum Group GmbH**, Schopfheim (DE)

(72) Inventor: **Thomas R Krauss**, Lorrach (DE)

(73) Assignee: **durlum Group GmbH**, Schopfheim (DE)

(**) Term: **15 Years**

(21) Appl. No.: **29/528,040**

(22) Filed: **May 26, 2015**

(30) **Foreign Application Priority Data**

Nov. 26, 2014 (EM) 002585455

(51) LOC (11) Cl. **25-01**

(52) U.S. Cl.

USPC **D25/161**

(58) **Field of Classification Search**

USPC D25/138, 139, 140, 141, 142, 143, 144, D25/145, 146, 147, 148, 149, 151, 152, D25/153, 154, 155, 156, 157, 158, 159, D25/160, 161, 162, 163, 106, 109, 114, D25/117, 120; D5/1, 2, 3, 5, 6, 8, 11, D5/12, 15, 16, 24, 29, 32, 43, 47, 54, 58, D5/53

CLAIM

The ornamental design for a ceiling tile or panel, as shown and described.

DESCRIPTION

The sole FIGURE is a plan view of a ceiling tile or panel in accordance with my design.

The broken lines represent the boundary of the claimed design and form no part thereof.

Thickness forms no part of the claimed design. The depicted surface of the ceiling tile or panel is flat. The lined/shaded areas depict a contrasting appearance from the unlined/unshaded areas.

1 Claim, 1 Drawing Sheet
